United States Patent Office

Des. 215,364
Patented Sept. 23, 1969

215,364

COPYING MACHINE

Charles W. Giebelhausen, Buffalo Grove, Ill., assignor to
Sescon Industries, Inc., a corporation of Illinois

Continuation of design application Ser. No. 9,726, Dec.
11, 1967. This application July 2, 1968, Ser. No. 12,691

Term of patent 14 years

Int. Cl. D14—02

U.S. Cl. D61—1

Fig. 1

Fig. 2FIGURE 1 is a front perspective view of a copying machine showing my new design; and

FIGURE 2 is a rear perspective view thereof.

The legible matter and indicia shown in broken lines is for illustrative purposes only.

This is a continuation of design application Ser. No. 9,726, filed Dec. 11, 1967.

I claim:

The ornamental design for a copying machine, as shown and described.
